UNITED STATES PATENT OFFICE.

WILLIAM J. WRIGHT, OF FRANKLIN, PENNSYLVANIA.

EXPLOSIVE-ENGINE.

974,455.

Specification of Letters Patent.

Patented Nov. 1, 1910.

Application filed February 17, 1908. Serial No. 301,688.

To all whom it may concern:

Be it known that I, WILLIAM J. WRIGHT, residing at Franklin, in the county of Venango and State of Pennsylvania, have invented a new and Improved Explosive-Engine, of which the following is a specification.

My present invention relates to explosive engines, and it seeks to provide certain improvements in said type of engines whereby to produce a compact, economical and effective operating mechanism, and by which an explosive impulse can be transmitted to the crank shaft at each quarter of its revolution.

In its more generic features, my invention comprehends two working cylinders and pistons therefor, and two pumping cylinders and pistons, the working cylinders each having a valved intake at each end, and a single valve mechanism for controlling the ports between the several working and pumping cylinders, being also employed.

Again, my invention seeks to provide an explosive engine in which the several parts are compactly arranged, and adapted for a positive and uniform operation, without the use of cams, eccentrics, and such like devices as are commonly used for shifting the feed and exhaust controlling devices, and in which the several parts are particularly designed for obtaining a maximum explosive force or power, under a minimum consumption of fuel.

Another and essential feature of my present invention, lies in a novel construction of governor mechanism for controlling the feed of the working agent, which forms a co-operative and interdependently acting part of the valve mechanism for controlling the feed, and in a more subordinate nature, my invention consists in certain novel details of construction and peculiar combination of parts, all of which will hereinafter be fully explained and specifically pointed out in the appended claims, reference being had to the accompanying drawings, in which:

Figure 1, is a side elevation of my improved "twin cylinder" engine, arranged in an upright position. Fig. 2, is a vertical longitudinal section of one of the working and pump cylinders, and the mechanism for joining the pistons of the two cylinders with the crank shaft. Fig. 3, is a detail plan

view. Figs. 4 and 5, are diagrammatic views illustrating the manner of operation of my invention. Fig 6, is a vertical section of the single valve mechanism for controlling the feed and the governor devices that form a co-operative part of said valve. Fig. 7, is a horizontal section of the said valve, taken on the line 7—7 of Fig. 6. Fig. 8, is a detail section of the same on the line 8—8 of Fig. 6. Fig. 9, is a detail section on the line 9—9 of Fig. 7.

In my present invention the essential features lie in the peculiar correlation with the working and pumping cylinders; in a novel construction of a combined valve and regulator mechanism, whereby by means of two sets of working and pumping cylinders, with a single valve mechanism, common to all of the pumping and working cylinders, I am enabled, in a compact and positive manner, to effect a driving impulse on the shaft on each quarter of its revolution.

Referring now to the accompanying drawings in which like letters and numerals of reference indicate like parts in all of the figures, A—A' indicate two working cylinders, B—B' indicate the pumping cylinders that respectively co-operate with the working cylinders A—A' and which, together with the cylinders A—A' are suitably mounted on the framing 1, as shown in Fig. 85 1 of the drawings.

While I have illustrated my present invention as an upright explosive engine, I desire it understood that the same may, with but slight changes in the supporting frame, be utilized as a horizontal engine.

As the details of construction of each set of pumping and working cylinders are the same, a description of one set of such parts, and the connections joining them with the 95 crank shaft will suffice for both.

By referring now more particularly to Fig. 2 of the drawings, it will be observed that the working cylinder has a valved intake *a* at each end, and a pair of closely disposed exhausts *b*—*b'* midway the ends of the cylinder which exhausts discharge into a single outlet *b*", as shown.

The valves of the intakes *a* are spring held to their closed position, and are arranged to open inwardly under a pressure of the working agent, as shown in Fig. 2, and as will be hereinafter more clearly apparent.

2 C—C' designate the piston rods of the two working cylinders, both of which are connected in a like manner with the crank shaft 100, the crank members 100^a of which are set on quarters.

Each pump cylinder B—B' has a port 5—5 at each end which ports alternately serve as inlets for a new charge from the feed pipe or valve, and as outlets for leading 10 the charge from the pump cylinders to the explosion ends of the working cylinders.

The piston rods D—D' of the pumps are coupled up with the actuating mechanism that joins with the working piston in such 15 manner that the pump and working pistons at certain times travel in unison in the same direction, and at other times have differential movement, the reason for the latter being as follows; in the complete arrangement 20 of one working cylinder and its co-acting pumping devices, the relation of the working cylinder and its pump is such that the charge is forced out of the pump cylinder in ahead of its piston into the working cylinder back of the working piston under a 25 low pressure. The pump piston is also arranged to force the new charge into the working cylinder in the rear of the working piston under a pressure barely in 30 excess of atmosphere so that the burned residuum in the working cylinder will be allowed to escape to atmosphere, and danger of loss of charge in blowing out such residuum as might remain back of the piston 35 is reduced to the minimum. The final pressure or force of the charge in front of the moving pump piston is exerted after the burned mixture is permitted to escape through the exhaust port of the working cylinder 40 and the piston therein begins to recover the said exhaust. To provide for the unitary action, as also for the differential action of 45 the two working and pumping pistons carried by the rods C—C', D—D', I join the piston rods C—C' each to a cross head E slideable on the frame section e and fulcrum a bell crank lever 20 to each cross head E and connect the short arm 20^a of the respective bell crank lever to the outer end of 50 the respective pump piston rod D—D', as the case may be, and connect the long arm of the respective lever 20 to the respective crank member 100^a of the crank shaft 100, as shown in the drawings, it being understood 55 that the connection between the short arms 20^a and the respective pump rods D—D' is made in such manner that the arc of movement of the arm 20^a will not interfere with the movement of the respective 60 pump rod D—D', as for example, by having the pivot pin carried by the respective rod D—D' operate in a slot or elongated hole in the respective lever arm 20^a, as shown in Fig. 2 of the drawings.

65 For convenience of operation and economy

of manufacture, the valve designated generally by the reference character F, is disposed about centrally of the two sets of cylinders and is suitably supported so that the drive pinion f, on the pendent axle stem 70 f' thereof will be in a plane with the crank shaft whereby to bring such pinion f into mesh with a drive pinion g of the same size on a countershaft G, suitably mounted on and geared with and deriving motion from 75 the main or crank shaft through gears g' and 100^b so that the valve F is brought into direct connection with the crank shaft. The gears 100^b and g' are preferably of the same size, it being understood that the size of the 80 gears f, g' and 100^b need not be the same but they should be, in practice, so proportioned that the speed of rotation of the valve shaft f' will be the same as that of the crank shaft 100. In other words, after each 85 revolution of the crank shaft 100 the valve shaft f' will make one revolution.

The valve F comprises a fixedly held base portion 10 having four sets of ports arranged in the manner best shown in Figs. 6 90 and 7, by reference to which it will be seen the four sets of ports are disposed 90° apart and are designated respectively by the characters 1^x—1^y, 2^x—2^y, 3^x—3^y, 4^x—4^y, two of which, 1^x—1^y and 3^x—3^y, are arranged to co-operate with one set of cylinders and the other two, 2^x—2^y and 4^x—4^y, co-operate with the other set of cylinders.

13 designates the rotatable member of the valve which is in the nature of a flat disk. 100 The member 13 is held to rotate on the upper face of the base portion 10. It has an annular opening 13^a, of a width sufficient to take in the several ports 1^x—1^y, 2^x—2^y, 3^x—3^y and 4^x—4^y, as it travels thereover.

Surrounding the member 13 and fixedly held on the base 10 is a cap or housing 14, which projects over and above the member 13 and forms the mixing chamber into which the mixed gas and air discharge and from 110 which the working agent escapes into the opening 13^a of the rotary valve member 13. The rotary valve member 13 has an opening o' in alignment with the opening 13^a but separated therefrom by a partition a⁵ and the opening o' does not extend entirely through the disk 13 so that it does not communicate with the mixing chamber in the housing 14.

The housing 14 has a central upwardly 120 extended tube 14^a, the end of which terminates in a flared valve seat 14^b and a flanged portion 14^c, for conveniently joining therewith the detachable feed tube 15.

16—16 designates a pair of centrifugal 125 governor balls hinged to studs 16^x—16^x on the upper face of the rotary valve member 13 and connected by the link arms 16^a—16^a, with a sleeve 16^b loosely held in the annular groove 17^a in the vertically shiftable valve 130

member 17, the upper end of which is closed and has a flared head 17^a adapted to engage the flared seat 14^a when closed down thereon to shut off the feed of gas or gasoline from the tube 15.

At its head end the member 17 has a number of feed apertures 17^a for the inflow of gas or gasoline. The member 17 is hollow and has its lower or discharge end formed with a restricted discharge 17^c. The housing 14 has air inlets 14^c controlled by the adjustable sleeve 18 which is also provided with openings and is adapted, when set, to regulate the inflow of air, as desired.

By providing a governor mechanism as described, and forming it with a part of the single controlling valve for regulating the flow of working agent to the several pumps and working cylinders, I have provided a very simple and inexpensive means for automatically controlling the flow of gas or gasoline to the mixing chamber. In operation, should the engine speed up beyond the normal, the valve 17 will be shifted down to close off its intake end, but in case the engine slows the valve 17 will be lifted by the spring connection 19 that joins the ball arms of the governor, as indicated particularly in Fig. 3 of the drawings.

In connecting the pump cylinder with its coacting working cylinder, to provide for the desired operation, the intake end (say the upper end) of the working cylinder is placed in communication with the lower end of the pump cylinder and the lower end of the working cylinder is placed into communication with the upper end of the pumping cylinder.

To provide for coupling the two sets of cylinders with the single valve F, the connections are made as best shown in Fig. 1 of the drawings, by reference to which it will be seen the pipe 11 connects with the upper end of the pump cylinder at the left of Fig. 1, and connects with the port 1^a which, under predetermined conditions of the rotary valve member 18, that is, when the annular opening, 18^a of such member is in register therewith, communicates through the said opening with the port 1^b with which the conveying tube or pipe 11^a joins and which connects with the valved intake of the lower end of the member 6 at the left of Fig. 4, as shown.

The lower end of the pump cylinder communicates with the other end of the cylinder A through the pipes or tubes 20^a and 20^b and the ports 2^a-2^b with the valve F, which ports are disposed diametrically opposite to the ports 1^a-1^b, before referred to. The opposite working and pump cylinders are correspondingly connected through the medium of the pipes 30-30^a-40-40^a with the ports designated respectively by the numbers 2^a-2^b, 4^a-4^b, which set of ports are ar-

ranged diametrically opposite one another and 90° from the other two sets 1^a-1^b and 3^a-3^b, as clearly shown in Figs. 4 and 5 of the drawings.

Operation: The manner in which my invention operates will be best explained as follows: Assume the exploded charge to be within the lower end of cylinder A in Fig. 4, and an exploded charge to be within the upper end of the cylinder A' in Fig. 4, and a new charge of working agent as being compressed in the upper end of the cylinder A in Fig. 4 and one in the lower end of cylinder A' in Fig. 4. Also assume the parts to be moving as shown by the arrows in Fig. 4. When the crank has arrived at the point α in Fig. 4, the working piston in the cylinder A will just about be ready to uncover the port 1^a and the valve F will be in a position just about ready to bring the ports 1^a-1^b into communication with one another through the passage o' of the valve. As the crank moves from the position α in Fig. 4, to the position α' in Fig. 4, the working piston in cylinder A will have uncovered the exhaust port 3^a to allow the exploded mixture to pass to atmosphere. At the same time the pump piston in the cylinder B will have moved to the position shown in dotted lines in Fig. 4, and the valve B will have moved to bring the ports 1^a-1^b into communication via the passage o', thus permitting the slightly compressed working agent ahead of the pump piston in cylinder B to pass through pipes 11-11^a via ports 1^a-1^b of valve F into the lower end of the working cylinder A and begin to drive out the exhausted charge through port 3^a.

As the crank moves from position α to position α' , the piston within the cylinder A' will be working under an exploded charge in the upper end of such cylinder and compressing a new charge in the lower end thereof. At this time also ports 2^a-2^b in the valve F will be in communication, no communication however, taking place between the upper end of the pumping cylinder B' and the lower end of the working cylinder A', owing to the back check valve that controls the inlet port to the lower end of the cylinder A' being closed. At this time also the pump piston in cylinder B' will be beginning to draw a fresh charge of working agent into the upper end of the pump cylinder B' through pipe 30 and port 2^a which is in communication with the mixing chamber of the housing 14 through the port 1^a of the valve F. At the same time (while the crank is moving from position α to α' in Fig. 4) the pump piston within cylinder B' will begin its downward movement to impart an initial compression to the new agent in the lower end of the pump cylinder B' in Fig. 4. Now as the crank moves from position α' to position α'' in Fig. 4, a quick

upward movement will be imparted to the pump piston in cylinder B, as shown in dot and dash lines in Fig. 4, to completely force the new mixture through pipes 11-11^x, via ports 1^x-1^y into the lower end of the cylinder A and at the same time the working piston in said cylinder A will have closed the exhaust port b', thus an initial compression is imparted to the new charge within the cylinder A.

While the crank is moved from position x² to the position x⁸ in Fig. 4, the working piston in cylinder A and the pump piston in cylinder B' are moving together in the same direction.

It should be understood that after the parts are in the position shown in Fig. 5, the pistons in the cylinders A'-B' will be performing substantially the same set of operations in the lower ends of said cylinders, as the pistons in cylinders A and B, in Fig. 4, are performing in the upper end of such cylinders, and a further description of the operation is thought to be unnecessary.

It should also be understood that the opening o' in the valve F is separated from the opening 13^a by a cross bridge piece o⁵, as shown in Fig. 7, of the drawings, and furthermore it does not communicate with the interior of the housing 14, but serves to form a bi-passageway between the two adjacent ports when over the same.

Having thus described my invention, what I claim and desire to secure by Letters Patent, is:

1. An improved explosive engine comprising two working cylinders and their pistons, and a pump for each working cylinder, piston rods for the pistons of the pumping cylinders, a crank shaft, operative connections between said crank shaft and said piston rods to cause said pumping and working cylinder pistons to operate in unison and move in the same direction under a part of their cycle of movement and to move in opposite directions during another part of that cycle of movement, a source of working agent supply, and an automatically controlled valve common to both pumps and working cylinders for leading the charge to said pumps and working cylinders successively and alternately into their opposite ends, substantially as shown and described.

2. An improved explosive engine, comprising two working cylinders, including a piston for each, said cylinders having a valved intake at each end, and a piston controlled exhaust common to both ends of the cylinder, a pump for each cylinder, having a valved combined intake and exhaust at each end, the combined intake and exhaust having a crossed connection with their respective coöperating working cylinders, a source of working agent supply, and a single valve mechanism, geared with the drive

member of the engine, adapted to control the feed to the pump inlets, whereby to feed to both pumps at the same time from opposite ends alternately and in succession.

3. An explosive engine, comprising a pair of working cylinders, having a valved intake at each end, and central piston controlled exhausts; of a pump for each cylinder, having a single opening at each end, a working agent controlling valve common to both pumps, and their working cylinders, and having independent ports, leads from said ports to each end of the working cylinder and the pump, the leads from the pumps through the single valve having a crossed over relation with their respective working cylinders, substantially as shown and for the purposes described.

4. The combination of the two working cylinders and their pistons, the pump cylinders and their pistons, coöperatively joined with their respective working cylinders, each pump having a single opening in each end, the working cylinders having a valved intake at each end, and a central piston controlled exhaust, the single drive shaft having a crank for each set of pump and working cylinders set on quarters, a rocking lever connection for joining the cross-head for each working cylinder piston with the shaft cranks and the piston rods for the pumps, a source of working supply, and a single valve mechanism common to both sets of working and pump cylinders, adapted to control the feed of the working agent to and from the pumps to the working cylinders in successive alternate intervals, for the purposes specified.

5. In an explosive engine as described, the combination with the working cylinders A-A' having a valved intake at each end, and a central piston controlled exhaust, the pumps B-B' having a single opening at each end, and coöperatively joined with the cylinders A-A', the drive shaft having two cranks on quarters, automatically shiftable connections for joining the pistons of the working and pump cylinders with the shaft cranks, a single valve mechanism common to both sets of pump and working cylinders, said valve having a separate set of ports for joining the ends of each pump cylinder with its coincident working cylinder, and in a crossed relation, whereby the pump cylinder at one end communicates with the working cylinder at the opposite end, and vice versa, a governor geared with the drive shaft, said governor including a shiftable valve member for controlling the flow of the working agent.

6. The combination with the two sets of working and pumping cylinders, and the feed connections 11-11^x, 20-20^x, 30-30^x, 40-40^x, for the two sets of working and pump cylinders; of the valve mechanism F,

said mechanism including a base having a series of ports 1^x—1^y, 2^x—2^y, 3^x—3^y, and 4^x—4^y, with which the leads 11—11^x, 20—20^x and 30—30^x and 40—40^x connect, the rotary member 13 having a feed opening co-operating with the several ports in the base member, the drive shaft controlled gear mechanism for imparting motion to the rotary

member, a feed to the valve, and a governor for said feed joined with and controlled by the movement of the rotary valve member, substantially as shown and described.

WILLIAM J. WRIGHT.
